SMOKING DEVICE

John T. Fisher, Indianapolis, Ind.

Application June 1, 1933, Serial No. 673,896
Renewed January 23, 1935

1 Claim. (Cl. 131—12)

This invention relates to a smoking device which may be used as a pipe, or a cigarette or cigar holder, the general object of the invention being to provide means whereby a cool and dry smoke 5 will be produced by the use of the device, with means whereby the device can be easily and quickly cleaned.

This invention also consists in certain other features of construction and in the combination 10 and arrangement of the several parts, to be hereinafter fully described, illustrated in the accompanying drawing and specifically pointed out in the appended claim.

In describing the invention in detail, reference will be had to the accompanying drawing 15 wherein like characters denote like or corresponding parts throughout the several views, and in which:—

Figure 1 is a longitudinal sectional view showing the device in use as a pipe.

Figure 2 is a view of the spreader or damper attached to its tube.

Figure 3 is a section on line 3—3 of Figure 1.

Figure 4 is a view of a cigarette holder.

Figure 5 is a view of a cigar holder.

In these views, the letter A indicates a stem which is composed of the outer part 1 and the lining 2, these parts being formed of any suitable material. The front or inner portion of 30 the stem is substantially cylindrical and the rest of the stem tapers to the tip 3. The opening in the tip slightly flares inwardly so that saliva from the mouth entering the tip will flow by gravity into the stem and thus not be carried back into the mouth and this configuration of 35 the stem will prevent moisture in the stem from reaching the mouth. The lining is extended beyond the front end of the part 1 and is exteriorly threaded to fit in the large part of the bushing 4 which fits in the short stem 5 of the bowl 6 of the pipe. The bushing is formed with a reduced neck 7 which is threaded in an opening in the lower part of the bowl and said neck is internally threaded to receive the threaded 40 end of a small tube 8, to the rear end of which is threaded a collar 9 carrying a pair of oppositely arranged rods 10 which support the rear end of a conical spreader or damper 11. The outer face of said spreader is flat and formed 45 with a kerf 12, as shown in Figure 3, so that a screw driver or the like can be used in placing the tube 8 in the neck 7 or removing it therefrom after the stem has been removed from the pipe stem.

50 Thus it will be seen that smoke from the bowl

can pass through the small tube 8 and as it passes through said tube, it will strike the conical part of the spreader or damper 11 and thus be directed toward the side of the stem so that the smoke will be cooled after contacting said side and any moisture in the smoke will be freed therefrom and collect in the large part of the stem. Thus the smoke will reach the smoker's mouth cool and dry.

By removing the stem from the stem of the 10 bowl, the interior of the stem can be readily cleaned, due to the large size of the bore and the tube 8 and the members 9, 10 and 11 can also be removed for cleaning purposes. Of course, if desired, the tube 8 and the spreader 15 need not be used.

Figure 4 shows an attachment for the stem A, so that the stem can be used as a holder for cigarettes. This attachment consists of a body part 13, preferably of the shape shown in Figure 4, and having its small end reduced and internally threaded, as shown at 14, to receive the tube 8, if the tube and spreader are to be used, and an internally threaded sleeve 15 is attached to the large end of the body in spaced 25 relation therefrom to receive the threaded end of the lining used with the stem. Thus by placing a cigarette in the body 13 and threading the body to the stem, said stem can be used as a cigarette holder.

Figure 5 shows an attachment 16 to be used with the stem so that the same can be used as a cigar holder. This attachment comprises a body having a large socket 17 therein for receiving the small end of the cigar and its other end is provided with a small internally threaded socket 18 for receiving the threaded end of the stem and this socket 18 is in communication with the socket 17 through a small threaded bore 19 which may receive the threaded end of the tube 8 so that the tube and spreader may also be used with the device when the same is used as a cigar holder. The use of the tube and spreader, however, is optional.

It is thought from the foregoing description 45 that the advantages and novel features of the invention will be readily apparent.

It is to be understood that changes may be made in the construction and in the combination and arrangement of the several parts, provided 50 that such changes fall within the scope of the appended claim.

What I claim is:—

A smoking device of the class described comprising a stem formed with a tip adapted to be 55

received in the mouth of the user, a lining extending from the tip through the stem with its front portion projecting beyond the stem, said projecting portion being externally screw threaded, a member threaded in said extended part, a tube carried by said member and extending into the front part of the bore of the stem, a collar

carried by the free end of said tube, a pair of oppositely arranged arms having one end connected to the collar and a conical spreader connected to the rear ends of said arms with its conical part directed forwardly.

JOHN T. FISHER.
